UNITED STATES PATENT OFFICE.

JOHN H. BARR, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,071,383.

Specification of Letters Patent. Patented Aug. 26, 1913.

Original application filed November 15, 1912, Serial No. 731,506. Divided and this application filed March 27, 1913. Serial No. 757,089.

To all whom it may concern:

Be it known that I, JOHN H. BARR, citizen of the United States, and resident of the borough of Manhattan, city of New York, in the county of New York and State of New York, have invented certain new and useful Improvements in Type-Writing Machines, of which the following is a specification.

My invention relates to carriage feeding or escapement devices for typewriting machines and its main object is to provide improved devices of the character specified.

To the above and other ends my invention consists in the features of construction, combinations of devices and arrangements of parts hereinafter described and particularly pointed out in the claims.

In the form of my invention illustrated in the accompanying drawings, Figure 1 is a fragmentary front to rear vertical sectional view of a No. 10 Smith Premier typewriting machine embodying my invention, only so much of said machine being illustrated as is necessary fully to disclose said invention. Fig. 2 is a fragmentary detail view showing a front elevation of the escapement mechanism. Fig. 3 is a fragmentary side elevation partly in section of Fig. 2. Fig. 4 is a perspective view of certain of the actuating devices shown in the preceding figures. Figs. 5 and 6 are sectional views of the escapement wheel, the sections being taken respectively transversely of said wheel and axially thereof. Fig. 7 is a detached view 35 of a part hereinafter referred to as a cam member. Fig. 8 is a fragmentary face view of a part or cover of the escapement wheel.

As shown in Fig. 1 the main frame of the machine comprises end plates 65 connected by a top plate 66 above which is mounted a stationary track-way 67 connected through anti-friction balls 68 with a carriage 69 supporting a platen 70 with the front face whereof cooperate type bars 71 pivoted at 45 72 and each connected through a train of devices comprising a link 73, a toggle element 74, a second link 75 and a bell crank 76 with a key stem 77 provided with a key 78. The toggle elements 74 are each fulcrumed as at 50 79 on a fixed support 80 and are provided with restoring springs 81. The tail portions 74^a of the toggle elements are adapted to actuate a curved universal bar or member 82 which is vertically disposed and is pivotally connected at about its middle at 83 to

an arm 84 on a rock shaft 85. At its sides said member 82 is connected by ears 86 with arms 87 rigid on a rock shaft 88 which rock shaft is connected to the rock shaft 85 in the usual or any other suitable way. Fixed to this rock shaft 88 is an upwardly extending arm 89 which is bent rearward at its upper end and terminates in a vertically disposed operating face 90 (Fig. 3). The carriage 69 is provided with a feed rack 91 with which mesh a pair of gear wheels 92 and 93 arranged face to face and having a lost motion connection as in the Smith Premier No. 10 machine. The gear wheel 92 is suitably connected with the usual carriage motor or spring drum 94 and the gear wheel 93 meshes with a pinion 95 which is loosely mounted on a horizontal shaft 96 extending fore and aft of the machine, said shaft bearing at its ends in pivot pins 97. The rear pivot pin 97 is supported on the spring drum casting 98 while the forward pivot pin is supported on a bracket 99 secured by screws 100 to a plate 101 fast on the casting 98, the shaft passing freely through an enlarged opening 101^a in said plate (Fig. 3). The pinion 95 is provided with a hub 95^a which abuts a washer 102 that engages with a novel escapement wheel hereinafter described and thus prevents forward movement of the pinion 95 along the shaft 96. Said pinion is provided with crown ratchet teeth which normally engage with corresponding ratchet teeth on a clutch member 103. Said clutch member is provided with fingers 104 which engage with notches formed in a flange 105 on the shaft 96. A coiled spring 106 is confined between the flange 105 and the head of the clutch member 103 and constantly presses the teeth of said clutch member into engagement with the crown ratchet teeth of the pinion 95.

Suitable releasing means (not shown) are provided for moving the clutch member rearward and thus in effect disconnecting the gear wheel 93 from the shaft 96 so that the carriage may move freely leftward under the action of the spring drum. Ordinarily, however, the carriage is connected with the shaft 96 as described and said shaft is controlled by escapement devices which are operative from the universal bar 82. These escapement devices comprise an escapement wheel 107 arranged on the shaft 96 between the plate 101 and the bracket 99. Said wheel 11

comprises (as clearly appears from Fig. 6) a hub or barrel portion 108 integral with which is a ratchet wheel 109 co-operative wherewith is a spring-pressed back pawl 110 5 of the usual construction (Figs. 2 and 3). The hub is bored out as indicated at 111 to fit over the shaft 96 to which it is secured by a set screw 112 that is received in a 10 tapped hole in the hub and abuts against the shaft 96.

Secured to the forward face of the ratchet wheel 109 by any suitable means is a dished plate 113 the periphery of which is formed with a series of notches 114 (Fig. 8). The 15 forward end of the hub 108 is slightly reduced as indicated at 108^a and receives a plate 115 which is provided with a series of tongues 116, said tongues being turned rearward at right angles to the plane of the 20 plate and fitting into the notches 114 in which said tongues are suitably secured. The plates 115 and 113 provide in effect a 25 hollow box in the periphery of which are a series of rectangular openings or slots 117 formed by the spaces between the tongues 116; said box being secured in rigid relationship with the ratchet wheel 109 and its hub and acting therewith as a single member or escapement wheel. Said wheel is 30 provided with relatively movable teeth or elements in the form of fingers 118, these fingers, of course, being arranged in place before the parts 113 and 115 of the box are 35 assembled. Said fingers as may be seen from Fig. 5 are shaped somewhat like key stones and are radially arranged, projecting radially outward from a common center which lies in the axis of rotation of the escapement wheel or rotary member. Each finger 40 has at its inner end a rounded teat 119 which fits loosely in a round guide hole 120, the series of guide holes 120 being formed radially in the front end portion of the hub 108 to the rear of the reduced end 108^a. The 45 outer end portions of the fingers 118 are reduced as indicated at 121, these reduced portions forming with the body portions shoulders 122 and projecting radially outward through the openings 117. These 50 reduced portions 121 are rectangular in cross section and provide a series of relatively movable escapement teeth.

As will be understood from Fig. 6 the fingers or toothed members 118 are adapted 55 to swing to a limited extent fore and aft of the machine within their receptacle or box 113, 115, owing to the fact that the part of the box farthest from the center is of somewhat greater depth than the height of 60 the toothed members due to the dishing of the cover plate 113. During the swinging movements of the members 118, the purpose of which is to provide for the escapement or step-by-step turning movement of the 65 escapement wheel and parts controlled

thereby, the shoulders 122 will slide back and forth over the inner faces of the tongues 116 adjacent the openings 117 in which openings the teeth proper 121 may move freely back and forth transversely of the 7 plane of rotation of the escapement wheel while the inner ends of the toothed members 118 are controlled by the guiding teats 119, the result being that the members 118 are in effect loosely pivoted in their containing element or holder. Twelve of these toothed members 118 are shown in the present instance but, of course, the number may be varied to suit the particular conditions of the construction in hand.

The movable teeth are adapted to co-act with a fixed arresting means or abutment which is shown detached in Fig. 7, said means being in the form of a plate 123, the right-hand end of which provides a vertical 8 stopping face 124 in the path of the teeth and for engagement thereby. The plate 123 is provided with an enlargement 125 which is secured by a headed screw 126 to the plate 101. A dowel pin 127 projects forward from 9 the plate through a hole in the enlargement and assists to prevent displacement of the plate 123. Said plate is off-set forward from the enlargement 125, as will be understood from Fig. 3, so as to be in the plane of 9 rotation of the teeth 121 when these are in operative position at the forward ends of the slots 117. In order to insure that the teeth are in line with, or in the plane of rotation of, the stop 123 as they near it 1 during the rotation of the element or wheel 107, a camming member or means 128 separate from said wheel is provided, said camming member being secured as by rivets 129 to the stop 123 and its free end being curved 1 or flared rearward to provide a cam surface to engage the teeth 121 when they are at the rear ends of the slots 117, said surface operating to cam or swing the teeth forward as the wheel is rotated in the direction of 1 the arrow in Fig. 2.

In order to disengage the teeth successively from the arresting means or face 124 so as to provide for a step-by-step escapement of the escapement wheel, devices are 1 provided comprising a pusher or actuator 130 horizontally disposed and pivoted at 131 at its forward end to a rocker member 132 which is best shown in Fig. 4. This rocker member comprises a crank arm portion 133 to which the actuator 130 is pivoted, and a hub portion 134 which is suitably secured to a rock shaft 135, the ends whereof are pivoted on adjustable screw pivots 136 supported in ears 99^a projecting 1 downward from the bracket 99. The hub portion 134 is provided with a leftward extension 137 having an enlargement 138 in which is secured a pin 139, the pin extending laterally rightward parallel with the 1

- extension 137 above the same, said pin being adapted to be actuated by the operating face 90 on the arm 89. These parts are normally separated as shown in Fig. 3. A coiled restoring spring 140 is secured at its forward end to a stationary pin 141 on the left-hand ear 99^a and at its rear end to the pin 139. The somewhat intricate character of the rocker member 132 is necessary in the present case to avoid interference with other parts. The actuator 130 is normally held up against a stop 142 on the rocker member by a wire spring 143. Said actuator passes rearward over a cut-out 128^a in the cam device 128 and its rear end normally lies just in front of the operative tooth 121. The right-hand side of the actuator is cut away to provide an inclined or cam face 130^a. The actuator is constantly acted on by the spring 140 which through the rocker 132 tends to draw said actuator forward, but this movement is controlled by stop devices comprising a stop pin 144 curving downward and rearward from the actuator 132 below its pivot and contacting with an adjustable screw-stop 145 secured to an ear 101^b on the plate 101 (Figs. 1 and 3).
- In operation, an actuation of one of the printing keys 78 acting through the toggle element 74 will move the universal bar 82 rearward and turn the rock shaft 88, causing the operating face 90 to swing rearward and contact with the pin 139, thereby swinging the rocker 132 rearward and causing the actuator 130 to push the operative tooth 121 toward the rear. This tooth it will be understood is maintained by the carriage motor or spring drum in engagement with the stop face 124 and as soon as said tooth has moved rearward transversely of the escapement wheel far enough to disengage from said stop face, the spring drum will operate to turn the wheel and cause a letter space movement of the carriage, the wheel being arrested by the engagement of the next succeeding tooth 121 with the stop face 124. If on release of the printing key the actuator should fail to swing bodily forward out of the path of the advancing tooth 121, the edge of said tooth acting against the cam face 130^a will cam the actuator 130 downward, said actuator swinging on its pivot 131 independently of the rocker out of the path of the advancing tooth which will move on until arrested by the stop face 124. Under such circumstances as soon as the actuator has swung forward out of contact with the tooth 124 it will be thrown upward on its pivot 131 by the spring 143 and will be in position at the next key actuation to contact with the front face of the engaged tooth 121 to disengage the same and permit a second letter space advance movement of the carriage. The teeth 121 after being successively moved out of the path of the stop face 124, will under ordinary conditions remain in rearward position in contact with the plate 113 as shown at the upper part of Fig. 6 until the rotation of the escapement wheel brings said teeth into co-action with the cam member 128 which will operate to swing the tooth forward into engagement with the plate 115 as shown at the lower part of Fig. 6 at which time the tooth will be in register or line with the stop 124.
- Among the advantages obtained from my present invention it will be observed that it provides for a full drop, the carriage moving the full letter space distance during the movement of a printing key in one direction. Another advantage is that the invention does away with the liability of skipping, which is a defect common to escapement mechanism particularly under rapid operation. By interposing a positive fixed abutment or arresting device in the path of the escapement wheel teeth it is impossible to obtain an accidental or undesired advance movement by reason of the abutment being pushed or cammed out of the way. The only manner in which an advance can be had is by moving the co-acting part, that is, the tooth of the escapement wheel, itself, and to do this a key operation is necessary. A third chief advantage is that I obtain uniformity in the timing of the escapement. In prior constructions, owing to the warping of the escapement's wheel itself, or to looseness in its mounting, it is impossible to avoid some variation in timing so that the let-off will take place at one time during the key stroke when one of the escapement wheel teeth is in operation, and at another and different time in a succeeding key stroke when another tooth is in operation. By employing in the present instance a single actuator and a single arresting device it is obvious that the timing of the escapement will always be the same no matter which of the movable teeth is in operation, for even though the time at which the different teeth are picked up by the actuator and consequently the extent of movement of said teeth may vary slightly, nevertheless, the time at which the teeth are moved out of engagement with the arresting means will always be the same.
- Various changes may be made without departing from my invention.
- Generic claims to the present construction have been made in the parent application, Serial No. 731,506, filed November 15, 1912, of which the present application is a division. The claims in the present case are specific to the form of invention herein disclosed.
- What I claim as new and desire to secure by Letters Patent, is:
1. In carriage feeding mechanism for

typewriting machines, the combination of a rotary element provided with a plurality of teeth, said teeth being movable on and independently of said element and being arranged to project radially outward from a common center which lies in the axis of said rotary element, stationary means co-operating successively with said teeth to arrest the carriage, and means for moving said teeth on said element into and out of position to coöperate with said first named means.

2. In carriage feeding mechanism for typewriting machines, the combination of an escapement wheel, radially arranged teeth thereon, a coöperative element, and means engaging successively with said teeth for moving them transversely of the plane of rotation of said wheel.

3. In carriage feeding mechanism for typewriting machines, the combination of an escapement wheel, teeth mounted to swing pivotally thereon independently of each other, said teeth being arranged to project radially outward from a common center which is contained in the axis of said escapement wheel, a fixed abutment coöperative successively with said teeth to arrest said wheel, and a key controlled actuator adapted to engage with said teeth when they are in contact with said abutment to release them from coöperation therewith.

4. In carriage feeding mechanism for typewriting machines, the combination of an escapement wheel comprising a box provided with slots in its periphery, teeth radially arranged within said box and movable in said slots, an abutment mounted on the frame of the machine and coöperative with said teeth, and a key controlled actuator for said teeth.

5. In carriage feeding mechanism for typewriting machines, the combination of an escapement wheel comprising a hollow box provided with slots in its periphery, teeth radially arranged within said box and movable in said slots transversely of said wheel, an abutment mounted on the frame of the machine and coöperative with said teeth, and a key controlled actuator for said teeth.

6. In carriage feeding mechanism for typewriting machines, the combination of an escapement wheel comprising a hollow box provided with slots in its periphery, teeth radially arranged within said box and movable in said slots transversely of said wheel, an abutment mounted on the frame of the machine and coöperative with said teeth, a key controlled actuator for said teeth, and a fixed cam for moving said teeth into position for co-action with said abutment.

7. In carriage feeding mechanism for

typewriting machines, the combination of a toothed escapement wheel, a coöperative abutment, an actuator for the teeth of said escapement wheel, a rocker on which said actuator is pivotally supported, and a key controlled member for operating said rocker, said member being normally disconnected from said rocker.

8. In carriage feeding mechanism for typewriting machines, the combination of a toothed escapement wheel, a coöperative abutment, an actuator for the teeth of said escapement wheel, a rocker on which said actuator is pivotally supported, a stop on said rocker for said actuator, a spring normally maintaining said actuator against said stop, and devices normally disconnected from said rocker for operating the same.

9. In carriage feeding mechanism for typewriting machines, the combination of a toothed escapement wheel, a coöperative abutment, an actuator for the teeth of said escapement wheel, a rocker on which said actuator is movably mounted, a stop on said rocker for said actuator, a spring normally maintaining said actuator against said stop, and devices normally disconnected from said rocker for operating the same, said actuator being also provided with an inclined or cam face with which said teeth are adapted to co-act to overcome said spring and move the actuator relatively to said rocker.

10. In a typewriting machine, the combination of type bars, actuating devices therefor, a curved universal bar operative from said actuating devices, a pivoted actuator operative from said curved universal bar, an escapement wheel provided with relatively movable teeth on which said actuator operates, an abutment adapted to coöperate with said teeth, a carriage, and connections between said carriage and said escapement wheel.

11. In a typewriting machine, the combination of type bars, actuating devices therefor, a curved universal bar, a pivoted arm, connections between said arm and said universal bar, a carriage, an escapement wheel provided with relatively movable teeth, said wheel being connected with said carriage, a coöperative abutment for said teeth, and a pivotally mounted actuator for said teeth, said actuator being operative from said arm.

Signed at the borough of Manhattan, city of New York, in the county of New York, and State of New York, this 26th day of March, A. D. 1913.
